UNITED STATES PATENT OFFICE.

ROSCOE B. KENDIG, OF PORT CHESTER, NEW YORK.

CAR-TRUCK.

1,086,672.

Specification of Letters Patent. Patented Feb. 10, 1914.

Application filed July 5, 1912. Serial No. 707,703.

To all whom it may concern:

Be it known that I, Roscoe B. Kendig, a citizen of the United States, residing at Port Chester, in the county of Westchester and State of New York, have invented certain new and useful Improvements in Car-Trucks, of which the following is a specification.

The invention relates to car trucks, and particularly to the coöperating side frame and journal box construction. The invention has for its primary objects, the provision of a simplified side frame and journal box structure in which the assembling and disassembling of the parts may be accomplished with the greatest of readiness and convenience, and the provision of a construction in which the necessity of using bolts and other removable securing devices is eliminated, and in which the journal box is maintained in position with a great degree of security by the weight of the side frame and the parts carried thereby. Certain embodiments of the invention are illustrated in the accompanying drawings, wherein:

Figure 1 is a side elevation of a truck side frame, broken away at its right hand end to show the attachment between the journal box and the frame and with the box shown in dotted lines in the process of removal at the left hand end of the frame; Fig. 2 is an end elevation of the side frame with the box in position therein; Fig. 3 is an end elevation of the side frame with the box removed; Fig. 4 is a side elevation of a modified construction of side frame and journal box; and Fig. 5 is an end elevation of the side frame of Fig. 4 with the journal box removed.

As shown in Figs. 1, 2 and 3, the side frame 1 of the truck is made in an integral casting provided at its ends with overhanging shelf portions 2 and also provided with the recesses 3. The journal boxes 4 are preferably made in one integral casting provided upon their inner sides with the hooks 5 adapted to engage the recesses 3. The sides of the recesses are closed so that the hooks 5 cannot move transversely of the plane of the side frame. The hook and recess engagement is such that the box may be disengaged when the side frame is jacked up by a downward swinging movement, the box being shown in the process of removal in dotted lines at the left hand end of the

side frame in Fig. 1. The shelves 2 lie upon the tops of the boxes 4 and are provided with overhanging portions 6 which prevent any movement of the boxes longitudinally of the side frame until the side frame is moved upward with respect to the boxes. The boxes themselves are provided with ridges 7 and 8 (Fig. 2) which engage the sides of the shelves 2 so that the boxes are held against movement transversely of the plane of the side frame until the weight of the side frame upon the boxes is removed by the upward movement of the side frame.

It will be seen from the foregoing that the journal boxes are held very securely in position by the weight of the side frame and parts carried thereby and that a displacement of the journal boxes cannot occur until the side frame is moved upward with respect to the journal boxes. After the side frame has been jacked up, the boxes can be very readily and conveniently removed by simply swinging the boxes downwardly and outwardly as there are no bolts or similar connecting means to detach; as is the case with the ordinary type of journal box. The parts marked 9 on the side frame provide convenient means for the application of lifting jacks when it is desired to remove the boxes or the wheels.

A modified type of construction is shown in Figs. 4 and 5 wherein a pivotal connection with the boxes and the side frame 1' is accomplished by means of the pairs of lugs 10-10 on the side frame (Fig. 5) and the lugs 11 on the journal boxes 4'. The lugs 10 and 11 are secured together by means of transverse bolts or pins 12 which may be held against accidental displacement by means of cotters or any other desired means. Inter-engaging means between the tops of the boxes and the shelves 2' are substantially the same as in the construction of Fig. 1. It will be seen that in this type of construction, the boxes will be held against entire disengagement from the side frame in case of derailment or accident wherein the shelves might otherwise be moved upwardly with respect to the boxes to such an extent as to permit the boxes to become displaced with respect to the side frame.

Having thus described my invention and illustrated its use, what I claim as new and desire to secure by Letters Patent is the following:

1. In combination in a car truck, a jour-

nal box having a hook on its inner side, and a side frame having a recess for the reception of the hook and an integral shelf portion extending over the top of the box, the hook and recess being so arranged that the box is detached from the side frame when the latter is elevated and the box rotated.

2. In combination in a car truck, a journal box, and a side frame having detachable pivotal connection with the inner side of the box and having a shelf portion extending over the top of the box.

3. In combination in a car truck, a journal box and a side frame having detachable pivotal connection with the inner side of the box and having a shelf portion extending over the top of the box and provided with means projecting down past the upper outer edge of the box.

4. In combination in a car truck, a journal box, and a side frame having detachable pivotal connection with the inner side of the box and having an integral shelf portion extending over the top of the box and provided at its edge with overhanging means preventing the outward movement of the box.

5. In combination in a car truck, a journal box, and a side frame having detachable pivotal connection with the inner side of the box and having a shelf portion extending over the top of the box, the box and shelf having interengaging means whereby the box is held against movement longitudinally or transversely of the side frame but which freely disengage when the box is rotated and the frame elevated.

6. In combination in a car truck, a journal box, and a side frame having an interlocking connection with the inner side of the box disengageable by rotary movement of the box with respect to the side frame and by the upward movement of the frame, and having a shelf portion extending over the top of the box.

7. In combination in a car truck, a journal box, and a side frame having an interlocking connection with the inner side of the box disengageable by rotary movement of the box with respect to the side frame

and by the upward movement of the frame, and having a shelf portion extending over the top of the box and having overhanging means preventing the outward movement of the box.

8. In combination in a car truck, a journal box, and a side frame having an interlocking connection with the inner side of the box disengageable by rotary movement of the box with respect to the side frame and by the upward movement of the frame, and having a shelf portion extending over the top of the box, the box and shelf having interengaging means preventing outward or lateral movement of the box until the side frame is moved upward with respect to the box.

9. In combination in a car truck, a side frame, a detachable independent journal box, and interlocking portions on the frame and the box securely holding the box against displacement when the latter is in operative position but permitting detachment of the box from the frame by relative movement of translation when the box is rotated and the frame elevated.

10. In combination in a car truck, a side frame, a journal box, and interlocking portions on the frame and box securely holding the box against displacement when in operative position, but automatically releasing when the frame is elevated and the box rotated.

11. In combination in a car truck a journal box, a frame to which the inner side of the box is rotatably secured, and a shelf portion on the frame extending over the journal box and provided with overhanging means abutting against the outer face of the box relieving the mounting of end thrust but freely disengaging from the box when the frame is raised and the box is rotated.

In testimony whereof I have hereunto signed my name in the presence of the two subscribed witnesses.

ROSCOE B. KENDIG.
